UNITED STATES PATENT OFFICE

JOSEPH GRANAT, OF SAN FRANCISCO, CALIFORNIA

DESIGN FOR A RING SHANK

Application filed December 27, 1929. Serial No. 33,941. Term of patent 3½ years.

To all whom it may concern:

Be it known that I, JOSEPH GRANAT, a citizen of the United States of America, residing at San Francisco, in the county of San Francisco and State of California, have invented a new, original, and ornamental Design for a Ring Shank, of which the following is a specification, reference being had to the accompanying drawing wherein the ring shank, the subject matter of this application is shown, in full lines and possible setting in dotted lines, forming a part thereof.

The figure is a perspective view of the ring shaft constituting my design.

I claim:—

The ornamental design for a ring shank substantially as shown and described.

JOSEPH GRANAT.
